UNITED STATES PATENT OFFICE.

EDWIN PEAK, OF CENTRALIA, FLORIDA, ASSIGNOR OF ONE-HALF TO JOHN H. GILBERT,
OF PLANT CITY, FLORIDA.

MOSQUITO-NET OR CANOPY HOLDER.

1,268,767.

Specification of Letters Patent.

Patented June 4, 1918.

Application filed August 3, 1917. Serial No. 184,304.

To all whom it may concern:

Be it known that I, EDWIN PEAK, a citizen of the United States, residing at Centralia, in the county of Hernando and State 5 of Florida, have invented certain new and useful Improvements in Mosquito-Net or Canopy Holders; and I do hereby declare the following to be a full, clear, and exact description of the invention, such as will 10 enable others skilled in the art to which it appertains to make and use the same.

This invention relates to improvements in mosquito net or canopy holders.

The object of this invention is to provide 15 a mosquito net or canopy support, which is capable of being removably secured to the head board of a wooden bed or iron bed and to the ceiling or the like and suspended in a manner as to completely cover the bed or 20 other device, such as a table or the like to prevent insects from getting in to persons occupying the bed or sitting at a table or the like.

Another object of this invention is to provide 25 a net or canopy support, which comprises a bracket, on which is journaled a supporting arm, in which is removably secured, a standard, which has an umbrella structure thereon, and the net is adapted to 30 be arranged over the supporting ribs of the umbrella structure so that it may completely cover the bed or the like.

A still further object of this invention is to provide a novel supporting means where- 35 by the device may be secured to a wooden bed, brass or iron bed, and one that can be removably secured to the wall or other sup- port.

A still further object of this invention is to 40 provide a device of this character, which will be simple, practical and comparatively inexpensive in construction, and one that can be manufactured and sold at a low cost.

With these and other objects in view, the 45 invention consists in the novel combination and arrangement of parts hereinafter more fully described and set forth in the claims hereto appended.

In the drawings:

Figure 1 is a side elevation partly in section to illustrate the manner in which the net is supported over a bed of the wooden type,

Fig. 2 is a side elevation partly in section

to illustrate the supporting means for the 55 wooden bed.

Fig. 3 is an enlarged detail sectional view of the manner in which the net is supported upon the supporting frame,

Fig. 4 is a perspective view of the support- 60 ing structure,

Fig. 5 is a perspective view of the support- ing arm,

Fig. 6 is a view illustrating the manner in which the device is attached to the hori- 65 zontal connecting bar of an iron bed,

Fig. 7 is a side elevation partly in section illustrating the manner in which the device may be removably secured to the wall of a 70 room or other support.

Like numerals of reference designate cor- 75 responding parts in all the figures of the drawings.

Referring to the drawings, the numeral 1 indicates the standard having slidably ar- 75 ranged thereon, a collar 2, which is limited in its downward sliding movement on the standard 1 by a spring 3. A conical collar 4 is secured as at 5 to the upper end of the standard and is provided at its lower end 80 with an annular exterior flange 6, and its upper end is provided with an annular flange 7. A plurality of supporting ribs 8 are pivotally secured as at 9 to the lower flange 6 of the collar 4. The ribs are ar- 85 ranged in a substantially rectangular plane and in annular formation or otherwise, two extending in one direction and two in the opposite direction at diametrically opposite points and one on each side thereof, thus 90 providing a rectangular supporting structure when in uppermost or extended position.

A plurality of stretching ribs 10 are piv- 95 otally secured as at 11 to each of the sup- porting ribs 8 and their free ends are piv- otally secured as at 12 to the sleeve 2, which is slidably arranged on the standard 1, thus it can be seen that the sleeve 2 is extended up beyond the spring 3 and the ribs 8 will 100 be in extended position as shown in Fig. 1. The type of construction described is similar to an ordinary umbrella structure.

The collar 4 is provided in its upper face with a centrally disposed inwardly extend- 105 ing screwthreaded bore in which is fitted the thread shank 13 of the bolt 14. The bolt is provided adjacent its head with an annular

flange 15, which is adapted to coöperate with the flange 7 on the upper end of the collar 4 to clamp a wear plate 16 therebetween. The wear plate 16 has secured thereto, at its peripheral edge, a mosquito net 17, which is adapted to extend beyond the ends of the supporting ribs 8 and downwardly in a vertical plane as at 19.

It can be readily seen that the net may be suspended over a wooden bed designated A and completely surrounds the bed by virtue of the supporting ribs 8 and the securing of the net through the medium of the wear plate 16 to the collar of the umbrella structure.

A supporting bracket comprises a rectangular vertical supporting plate 20, which is provided adjacent each end with openings 21. The rear face of the supporting plate 20 is provided with a transversely extending slot 22, which extends out through one vertical side edge thereof as shown in Fig. 4. An L-shaped bracket 23 has the terminal of one flange enlarged as at 24 and this flange is adapted to be fitted in the groove 22 of the supporting plate to facilitate the removable securing of the supporting plate to the head board of the wooden bed A. The vertical flange of the L-shaped bracket 23 is provided with a screw-threaded opening 25, in which is removably fitted, a thumb screw 26, which facilitates the removable securing of the supporting plate 20 to the head board of the wooden bed as shown in Fig. 1.

A horizontal arm 27 has one end formed integrally with the front face of the supporting plate as at 28, and its opposite end is provided on the upper side thereof with a vertically arranged cylindrical member 29, which has a reduced extension 30 formed centrally on the upper side thereof. The reduced extension forms a horizontal bearing surface 31 in cross section at its point of juncture with the cylindrical member 29 as shown in Fig. 4.

A supporting member 31' has one end bifurcated as at 32 and offset as at 33 and the bifurcated portion 32 is offset laterally to provide the annular interior surface. The terminals of the arms defined by the bifurcated portion extend in spaced parallel relation as at 34 and are provided with aligned transverse openings 35 through which is removably fitted a thumb screw 36 which facilitates the moving of the parallel portions 34 toward one another for clamping the offset portions about the rail of an iron bed or the like, as shown in Fig. 6.

The free end of the bearing member 31 terminates in a cylindrical apertured member 36', which is adapted to receive the lower end of the standard 1, which standard is removably held therein by a thumb screw 37, extending transversely through the cylindri-

cal member 36 and has its inner end bearing against the standard 1 to permit the same to be adjusted therein.

The member 31 is provided intermediate its ends with an offset apertured enlargement 37, which is adapted to be rotatably mounted upon the extension 30 of the supporting structure 20, thus facilitating the supporting of the net directly over the bed, permitting the same to completely encompass the bed, preventing insects, such as flies, mosquitoes and the like from entering and disturbing the occupants of the bed.

It is to be understood that when the device is used in connection with a wooden bed, the structure illustrated in Figs. 1, 2 and 4 is used, the L-shaped bracket is clamped to the upper side of the head board as shown in Fig. 1 through the medium of the thumb screw 26, the supporting arm or member 31' is rotatably mounted on the extension 30 and the standard is adjustably mounted in the cylindrical member 36' and the arm 31' is held therein through the medium of the thumb screw 37', the sleeve 2 is forced upwardly beyond the spring 3 and thus the ribs 8 are in extended position, the net is removably arranged over the ribs and the supporting member is arranged on the upper side of the collar 4, the bolt 14 is then fitted in the collar 4, securely holding the net thereto, and the device is assembled in the manner shown in Fig. 1 and is ready for use in connection with a wooden bed.

When it is desired to use the device in connection with a table or the like for a covering therefor or for a bed, and the device is to be attached to the wall, it is only necessary to remove the L-shaped bracket 23 out of the slot 22 and secure the vertical plate 20 to the wall designated B by suitable fastening means 38, which extend through the openings 21 of the plate 20 and into the wall as shown at 39.

When it is desired to use the same in connection with an iron bed, of annular supporting structure, it is only necessary to remove the arm 31' from the extension 30 and arrange the offset portions 33 about the iron foot board of the bed designated C in the drawings and arrange the bolt 36 through the parallel portions, thus clamping the offset portions 33 about the annular or cylindrical member of the iron bed and the device is ready for use.

What is claimed is:

1. A mosquito net or canopy holder comprising a vertical attaching plate, an L-shaped bracket removably secured by one flange to the rear face of the plate, a horizontal arm formed integrally with the opposite end of the plate and extending outwardly therefrom, a vertical cylindrical member formed integrally with the upper face of the horizontal arm at the free end

thereof a cylindrical extension formed integrally with the cylindrical member, an arm rotatably mounted on the extension, a mosquito or canopy supporting standard removably arranged on the outer end of the last named arm.

2. A supporting structure for a canopy or net comprising a vertical plate provided adjacent each end with openings, the rear 10 face of said plate provided with a transverse groove opening out through one vertical edge thereof, an L-shaped bracket having an enlarged member and one flange removably arranged in the transverse groove 15 of the plate, said vertical flange of the L-shaped bracket facilitating the securing of the plate to the foot board of the bed, a horizontal arm formed integrally with the front face of the plate, a vertical cylindrical 20 member formed integrally with the upper side of the horizontal arm at the outer end thereof, and a reduced cylindrical extension formed integrally with the upper side of the cylindrical member, and a supporting 25 arm rotatably mounted on the extension and provided with means at the outer ends thereof to removably and adjustably support the mosquito net or canopy holding device.

3. A mosquito net or canopy supporting structure including a vertical plate pro-

vided adjacent each end with transverse openings, said plate provided on its rear face with a transverse dove-tail groove extending out through one vertical side edge 35 thereof, an L-shaped bracket having the terminal of its horizontal flange enlarged to be removably arranged in the transverse groove of the plate, the vertical flange of 40 said bracket being in spaced relation to and parallel with the supporting plate, means extending through the vertical flange for removably securing the plate to the head board of a bed, a horizontal arm having one end formed integrally with the front face 45 of the plate, a cylindrical extension formed integrally with the upper side of the horizontal arm at the outer end thereof, a reduced cylindrical extension formed integrally with the cylindrical member, an arm 50 rotatably mounted on the extension, the outer end of said arm provided with a cylindrical aperture member to facilitate the adjustable and removable supporting of the device for supporting the canopy or mosquito netting over a bed.

In testimony whereof I affix my signature.

EDWIN PEAK.
